UNITED STATES PATENT OFFICE.

EDWARD PERRIN, OF KIDDERMINSTER, ENGLAND, ASSIGNOR TO JOSEPH WILD & CO., OF NEW YORK, N. Y.

DESIGN FOR CARPET.

Specification forming part of Design No. 6,233, dated October 29, 1872.

To all whom it may concern:

Be it known that I, EDWARD PERRIN, of Kidderminster, in the county of Worcester, England, have invented a new and original Design for a Carpet, of which the following is a specification:

The accompanying photograph fully illustrates my new design.

This invention relates to a new carpet-design in which two octagonal main figures are in absolute contact and apparently grown into one another. One of these figures has a square field in the middle, and the portion surrounding the square subdivided into eight fields, which have marbleized groundwork, as shown.

The other figure has semicircular protuberances on four of its eight sides entering the adjoining octagons of the first-mentioned kind. An eight-pointed star is arranged within this second kind of octagon, and surrounded by floral scrolls, while embracing a rosette, as shown.

I claim as my invention—

The design for a carpet, as shown.

EDW. PERRIN.
